PANIC BOLT

Ellis J. G. Phillips, Aurora, Ill., assignor to Richards-Wilcox Manufacturing Company, Aurora, Ill., a corporation of Illinois

Application August 2, 1940, Serial No. 349,777

19 Claims.

(Cl. 292—92)

My invention relates to emergency release door latches frequently referred to in the trade as panic bolts.

In situations where crowds are gathered, such as in theaters and assembly halls, there is always the danger of people becoming injured from the rush of the crowd in case of fire or other imminent danger. In such danger, the impulse of the crowd is to charge blindly against any closed door in an emergency exit and if there is any delay or difficulty in getting the door open many persons are likely to be crushed or trampled on by the crowd. Any such door must afford a means of escape which is operable automatically and which does not require thinking by the fleeing crowd. It is therefore an object of my invention to provide an emergency door latch which will operate on the first contact of a person against it.

Another object of my invention is to provide a latch which can be operated from outside the door as well as from the inside, and which can be locked against operation from the outside without interference with the automatic release from the inside.

Another object of the invention is to provide a latch which will in ordinary circumstances serve as a spring door latch with the additional feature of emergency release when needed.

The door is provided with a bar which will operate to trip the latch when pressure is exerted against the bar, and continued pressure will force the door open. This bar is located in such a position that contact by any person, whether an adult or a child, will operate it. It is an object of the invention to provide an operating bar which will move horizontally when pressure is exerted against it, as distinguished from downward movement which is a feature of most such release latches, thus eliminating rubbing of the bar against a person's body since in horizontal movement of the bar the body will move along with it.

Another important object is to provide a release bar for the latch which can be grasped by the hand and operated without danger of pinching the hand when it is operated.

Another object of the invention is to provide a device which is characterized by its simplicity of design and low cost of manufacture.

Other objects and advantages of the invention will be apparent to those skilled in the art from the following detailed description taken in conjunction with the accompanying drawings, in which:

Figure 1 is a plan view of a door embodying my invention;

Figure 2 is a view similar to Figure 1 but showing the operating parts of the device in an alternate position;

Figure 3 is an elevational view of the device shown in Figures 1 and 2;

Figure 4 is a fragmentary view similar to Figure 2 showing the device as being operable by two different means;

Figure 5 is a view taken on the line 5—5 of Figure 1;

Figure 6 is a view taken on the line 6—6 of Figure 1;

Figure 7 is a view of a modified form of the device of my invention;

Figure 8 is an end view of the device shown in Figure 7;

Figure 9 is a plan view of the embodiment shown in Figure 7;

Figure 10 is a view similar to Figure 9 but showing the operating parts in an alternate position;

Figure 11 is a front elevational view of another modification of my invention; and

Figure 12 is a plan view of the device shown in Figure 11.

Figure 13 is a plan view of a modified form of release latch;

Figure 14 is an elevational view of another form of release latch;

Figure 15 is a plan view of the device shown in Figure 14;

Figure 16 is a sectional view taken on the line 16—16 of Figure 15, on an enlarged scale;

Figure 17 is a sectional view taken approximately on the line 17—17 of Figure 14;

Figure 18 is a sectional view of the latch bolt assembly used with the form of device of Figure 14; and

Figure 19 is an elevational view showing two forms of latches cooperating to retain double doors closed.

Referring now in detail to the drawings, a door is indicated generally by the reference numeral 11 which is supported by hinges 12 in a wall 13 for outward swinging movement. A jamb 14 is positioned at the other end of the door and secured to the jamb is a latch bolt keeper 15 adapted to be engaged by a latch bolt on the door to hold the door closed. On the inside of the door is provided a bar or rail 16 against which a person may exert pressure to operate the device and open the door in case of emergency. Mounted on the door are two plates 17 and 19 each with pro-

jecting lugs 20 in which levers 21 and 22 respectively, may be pivoted on pins 23. The opposite ends of the levers 21 and 22 are pivoted in U-shaped brackets 24 and 25, respectively, see Figure 5, which are welded or otherwise suitably secured to the bar 16.

A lock assembly, indicated in its entirety by the reference numeral 26, is located near the closing end of the door and comprises a housing 27 which is bolted or otherwise suitably secured to the door by means of ears 29 which extend outwardly from the housing 27. Positioned within the housing is the usual latch bolt 30 provided with a tapered edge 31 which rides over the keeper 15 in the closing motion of the door. A reduced shank 32 is attached to the rear end of the latch bolt and extends outwardly of the housing 27 and is surrounded by compression spring 34 which reacts between the latch bolt and the rear end of the housing 27 to bias the latch bolt to latched position. Pivots connected with the reduced shank 32 of the latch bolt are a pair of links 35, the other ends of which are pivoted at 36 at the point of connection between the lever 21 and the bracket 24.

On the outside of the door is mounted a bracket 37, bolted to the door or otherwise secured as desired, having lugs 39 in which is pivoted an outside release handle 40. The handle is suitably shaped for grasping by the hand and is provided with a forked member 41, see Figure 6, which extends through the door and fits over the reduced shank 32 of the latch bolt to have a one-way motion transmitting connection with the latch bolt. The other end of the handle has an aperture 40' for locking the handle. In the position of the handle in Figures 1 and 2 it may be locked by a padlock 42, or similar device, by passing the hasp of the lock through the aperture 40' and through a corresponding aperture in a bracket 43, which bracket is bolted on the outside of the door next to the handle.

In the position of the device shown in Figure 1, the latch bolt is in locked position, being held in this position by the spring 34 and the bar is in outwardly deflected position, i. e., away from the door. When pressure is exerted against the bar from the inside of the door, the levers 21 and 22 turn about their pivots 23 in a counterclockwise direction, and consequently the bar will follow the movement of the levers and will be forced inwardly toward the door and also at the same time laterally of the door in a direction away from the jamb 14. In this motion away from the jamb 14, the bar will unlock the latch bolt 30 through the links 35. Figure 2 shows the bar 16 in its innermost position against the door. The levers 21 and 22 are so shaped that when they reach the position shown in Figure 2 the bent portions of the levers will abut against the door and act as a check against further movement of the bar 16. As will be seen from these two figures the latch may be operated by the bar 16 without interference by the outside release handle 40, and it may even be accomplished when the handle 40 is locked against movement, since the forked member 41 merely has a one-way motion transmitting connection against shoulders 35' projecting outwardly from the adjacent end of the links 35. This is also true even if the outside release handle 40 should be temporarily frozen against motion by snow or ice.

The U-shaped brackets 24 and 25 are of appreciable length so that the bar 16 is positioned at some distance from the point of connection of

the links 35 with the bracket 24, and if the bar should be grasped by the hand between it and the links 35, the hand will not be injured as the bar is forced toward the door. The bar 16 has only limited movement toward the door because the stop shoulders 21' and 22' on the levers 21 and 22, respectively, abutting against the door prevent the bar 16 from being moved any closer to the door than the position it occupies in Figure 2, where it can be easily seen that there is ample space between the bar and the links 35. It is obvious that no matter where the bar 16 is grasped pinching of the hand is prevented, and this safety feature is not limited to the space between the bar and the links 35.

Figure 4 shows the operation of the device from the outside by means of the handle 40. The handle, when it is grasped and pulled outwardly from the door, pivots about the pivot 38, and the forked extension 41, which is integral with the handle 40, consequently rotates with it and acts to unlatch the latch bolt. Thus it will be seen that the device can be operated from either side of the door, and it can be locked against operation from outside the door, while at the same time allowing the emergency release to operate from the inside.

In Figures 7 to 10, inclusive, is shown an application of the operating bar of the previous embodiments to a different form of latching means. The reference numeral 11 indicates the door generally, and at the top and bottom are latch bolt keepers 45 and 46 against which latch bolts are adapted to engage to hold the door closed. A latching assembly 47 is secured at the top of the door and a similar latch assembly 49 is secured at the bottom of the door, and each is provided with a latch bolt 50 with the usual reduced shank 51 and compression spring 52 for biasing the latch bolt to latched position. Mounted on the door is a plate 54 on which are pivoted two bell crank levers 55 and 56. Links 57 and 59 are attached to respective latch bolts 50. Link 57 is adjustably secured to the bell crank lever 55 at 60, and link 59 is adjustably secured to bell crank lever 56 at 61.

An operating bar 62, similar to that of the previous embodiment, is pivotally connected to the door by means of parallel levers 64 and 65. Levers 64 and 65 are pivotally connected at 66 and 67 to the U-shaped brackets 69 and 70 which are welded or similarly secured to the bar 62. The other ends of the levers 64 and 65 are pivoted in brackets 71 and 72 which are bolted or otherwise suitably secured to the door. Upper and lower links 73 and 74 are connected between the bell crank levers 55 and 56 and the point of connection 66 between the lever 64 and the bracket 69. Also as in the previous embodiment, the levers 64 and 65 are shaped with shoulders 64' and 65', respectively, which are adapted to abut against the door.

The operation of the device is very similar to that of the previous embodiment. When pressure is exerted against the bar 62, it is forced inwardly against the door and in such movement the levers 64 and 65 rotate about their pivot points in the brackets 71 and 72 in a clockwise direction and as a result the bar 62 is at the same time forced to the left as shown in Figures 9 and 10. Through this movement the links 73 and 74 rotate the bell crank levers 55 and 56 about their pivots to the positions shown in dotted lines in Figure 7, drawing the latch bolts 50 to released

positions. The shoulders 64' and 65' abutting against the door prevent movement of the bar any further than the position which it occupies in Figure 10. The U-shaped brackets 69 and 70 are made of considerable length so that when the bar 62 is in its foremost position toward the door there is sufficient space between the bar and the links 73 and 74 and there is no likelihood of the hand being pinched when the bar is grasped; and of course if the bar is grasped in any other place there is also no danger of pinching the hand.

In Figures 11 and 12, I have shown another modification in which means operable from the outside of the door is applied to the embodiment shown in Figures 7 to 10. The door is indicated by the numeral 11 and mounted thereon is the plate 54 which pivotally supports the bell crank levers 55 and 56. A portion of the operating bar 62 and the upper and lower links 73 and 74 connecting the operating bar 62 with the bell crank levers 55 and 56 are shown.

A handle 75 is mounted on the outside of the door 11 in a bracket 76 in which it is adapted to pivot on operation thereof. An extension 77 is formed integral with the handle 75 and extends through an opening 79 in the door 11. The end of this extension is in the form of a vertical flange or plate which occupies a position just to the right of the ends of the links 73 and 74 and the corresponding ends of the bell crank levers 55 and 56 to which the links are connected, said extension thus being in position to exert a pushing force to the left on the vertical arms of the bell crank levers.

A person grasping the handle 75 from outside the door will turn it about its pivot in the bracket 76 in a clockwise direction, forcing the end of the extension 77 to the left and releasing the latches on the door. This operation has precisely the same effect in unlatching the door as movement of the bar 62 toward the door. However, because of the one-way motion transmitting connection between the outside handle 75 and the latching means, the release bar 62 can release the latching means without necessitating that the outside handle move concurrently therewith. Provision may be made for locking the handle 75 against unauthorized operation, substantially as previously described in connection with Figures 1 and 2.

In Figures 13 to 19, inclusive, are shown horizontally and vertically disposed latching devices. The horizontal device is shown in Figure 13 in which the numeral 85 indicates a door, 86 a door jamb at the closing edge of the door, and 87 suitable keeper means for retaining the door in latched position and against which the door abuts in its closing motion. Mounted on the inside of the door near its closing edge is a latch bolt assembly 89 which comprises a housing 90 in which is mounted a latching bolt 91 provided with an inclined surface 92 and a reduced shank portion 94. The inner end of the reduced shank 94 is slidably mounted in a guide extension 95 formed on the inside of the housing 90. This end of the shank 94 is of forked formation and between the prongs of the fork is mounted a roller 96.

A release bar 97 is mounted on the inside of the door on parallel levers 99 which are pivoted in U-shaped brackets 100 welded or otherwise secured to the bar, and in brackets 102 riveted or otherwise suitably secured to the door 85. One end of the bar 97 is formed with an inturned

arm 104 which is adapted to fit between the prongs of the inner end of the shank 94 and bear against the roller 96, thereby establishing a one-way motion transmitting connection between the release bar 97 and the shank 94 of the latching bolt. The other end of the bar 97 is formed with an arm 105 which engages in a slot 106 formed in housing 107 which is secured to the door and acts as a guide for the arm 105 and thereby the bar 97. When pressure is brought to bear on the bar 97 towards the door, it will pivot on the levers 99 and be forced to the right as shown in Figure 13 and inwardly toward the door to the position shown in dotted lines. When this occurs, the arm 104 bearing against the roller 96 will force the latch bolt 91 to the right as shown in Figure 13, releasing the latch bolt from the keeper means 87 and enabling the door to be opened. A slot 109 is formed in the housing 90 to accommodate the movement of the arm 104 when operating the latch bolt.

The extent to which the bar 97 can be moved in relation to the door is determined by the slot 109, the arm 104 engaging one or the other end 25 of the slot. The limit to which the bar can be forced inwardly toward the door is that position shown in dotted lines where it can be seen that the arm 104 is to the right in the slot 109 and bearing against the end of the slot. The brackets 30 100 are of considerable length so that the bar 97 will not fold up against the levers 99 but will be spaced some distance therefrom and this feature together with the fact that the bar has only limited movement prevents any pinching of the 35 hand between the bar 97 and the levers 99.

Mounted on the outside of the door is a bracket 110 in which is pivoted a handle 111 provided with an integral arm 112 which extends through an opening in the door to the inner side thereof 40 into the housing 90. Mounted on the inner side of the door within the housing 90 is a guide bracket 114 for supporting a slide bar 115 provided with an inturned projection 116 for engaging a stud 117 secured in the latch bolt 91. The 45 arm 112 extending from the outside handle 111 has operative engagement in an aperture in the slide bar 115, and the above described arrangement of parts establishes a one-way motion transmitting connection between the outside handle 111 and the latching bolt, whereby the latching bolt can be released through releasing movement of the inside release bar without compelling concurrent movement of the outside handle 111. By grasping the handle 111 and pulling it outwardly from the door, i. e., in a 50 counterclockwise direction as viewed in Figure 13, the arm 112 will force the slide bar 115 to the right engaging the stud 117 and thereby forcing the latch bolt to the right and releasing the latch bolt from the keeper means 87. Surrounding the shank 94 and reacting between the head of the latch bolt and the extension 95, is a compression 55 spring 93 which forces the latch bolt to latched position when the pressure is released from the bar 97 and the handle 111. By this arrangement it can be seen that the door can be opened either from the inside or the outside, and if desired, means such as shown in Figure 1 may be provided 60 on the outside of the door for locking the handle 111 against operation to permit opening of the door only from the inside.

Another form of locking means for locking the operating handles 40 and 111 against movement 75 is shown in Figures 1, 13 and 19. In Figure

19, a key operated lock 97', of the sliding latch type is shown diagrammatically. In this form the sliding latch 92' shown in Figure 13, acts as a stop for the slide bar 115. The sliding latch 92' also performs the same function with respect to the member 41 shown in Figure 1.

Figures 14, 15 and 16 show an arrangement similar to that of Figure 13 applied to vertical latching means at the top and bottom of the door. Mounted on the inside of the door 118 is a release bar 119 mounted on parallel levers 120 which are pivoted in U-shaped brackets 121 welded or otherwise secured on the bar 119 and in brackets 122 secured to the door. The bar 119 is provided with an inturned arm 124 which fits through a slot 123 in a housing 125 for operating a mechanism therein that actuates the latching means, as will be described later. The other end of the bar 119 is provided with an inturned arm 126 which fits into a slot 127 of housing 129 for guiding that end of the bar 119. At the top and the bottom of the door are latch means 130 with the usual latch bolts 131 engageable with keeper means 132 mounted on the top door jamb and the floor. From each latch assembly 130 is a link 134 connected with the latch bolt 131 and having an adjustable connection with the operating mechanism contained within the housing 125.

As described in connection with Figure 13, in this form also the bar 119 is arranged so that there is no pinching of the hand between the bar and the levers 120. The arm 124 sliding in the slot 123 limits the movement of the bar 119, and the brackets 121 are of sufficient length that the bar and the levers will not fold up together.

Reference should be had to Figure 16 for a view of the mechanism contained in the housing 125. A pinion 135 is carried by a stud 136 mounted on the door, and also carried by the stud and driven by the pinion is a collar with oppositely disposed ears 137 to which the links 134 are connected. A slide 139 is slidably positioned in the housing 125 and is provided with a pair of upwardly extending lugs 140 and 141 in which is mounted a roller 142. Secured to the lug 141 is a rack 144 which engages the pinion 135 and is adapted to actuate the latter. The arm 124 of the bar 119 bears against the roller 142 as shown in this figure, thereby establishing a one-way motion transmitting connection between the release bar 119 and the latch releasing slide 139. When pressure is exerted on the bar 119 toward the door, the bar swinging about the links 120 will be forced to the left as shown in Figure 15, and thereby the arm 124 of the bar 119 bearing against the roller 142 will force the slide 139 and consequently the rack 144 to the left as shown in Figure 16, thereby rotating the pinion 135 in a clockwise direction. As a consequence of this operation, when the pinion 135 is rotated, the collar with the ears 137 will also be rotated and the links 134 will be actuated inwardly toward each other, releasing the latch means 130 and enabling the door to be opened. Figure 17 shows the shape of the housing 125 in cross-section and the manner in which the slide 139 is held in position therein. With the housing 125 mounted on the door, the left hand side of the housing becomes the bottom, and the surface 145 supports the slide 139 in position therein. This prevents any binding action between the arm 124, the slide 139, and the pinion 135.

Figure 18 shows the latching assembly 130,

which comprises a housing 146 in which is slidably mounted the latch bolt 131. The latter comprises a reduced shank portion 147 with its inner end of forked formation and slidably mounted in a projection 149 formed on the inner side of the housing. Between the prongs of the forked inner end of the shank 147 is carried a roller 150. Secured on the inner end of the link 134 is a collar 151 with a projection 152 fitting between the prongs of the forked inner end of the shank 147 and engaging the roller 150. When the link 134 is actuated it draws the latch bolt 131 into the housing, enabling the door to be opened, and when pressure on the link 134 is released, a spring 154 surrounding the shank 147 and reacting between the head of the latch bolt and the projection 149 forces the latch bolt to latched position. A bracket 153 limits the extent to which the link 134 may be retracted into the housing 146 and consequently the extent to which the latch bolt 131 will be extended.

Figure 19 shows the manner in which the two latching devices shown in Figures 13 and 14 may be used in cooperation with double doors for securing them closed. The door to the left, 118, is provided with the latching device shown in Figure 14, and the latching bolts 131 engage keeper means on the top jamb and on the floor, thus holding the door closed. At the closing edge of the door 118 is a keeper plate 156. The door 85 is provided with the latching device shown in Figure 13. When in closed position, the latching bolt 91 thereof will engage the keeper plate 156, thus holding that door closed. With this arrangement, either door may be opened first whether the other door is open or not, and when the door 118 is opened first the other door will be in unlatched position. This arrangement may be used also in connection with the forms of devices shown in Figures 1 and 7.

While I have shown specific embodiments of the invention, it is to be understood that I do not intend to be limited to the details shown and described but that all arrangements of parts to meet particular adaptations, and substitution of equivalents are to be within the scope of the invention.

I claim:

1. In apparatus of the class described for a door, the combination of a plurality of latch means for retaining the door closed, links connected to said latch means, a rack and pinion operating through said links for actuating said latch means, a bar for operating said rack and pinion, brackets secured to said bar, and parallel levers pivoted on the door and said brackets and thereby supporting said bar for horizontal movement toward and away from the door, said brackets being of substantial length for spacing said bar from the points of connection of said brackets with said levers whereby when said bar is in its foremost position toward the door space is provided between said bar and said levers for grasping by the hand.

2. In apparatus of the class described for a door, the combination of latch means, a latch keeper engageable by said latch means for retaining the door closed, a bar, parallel levers pivoted on the door and on said bar for mounting said bar on the door in spaced relation thereto, a roller operative to actuate said latch means, said bar having an inturned arm extending toward the door and engaging said roller for actuating said latch means, said bar being adapted to swing on said parallel levers horizontally

toward the door and away from said latch keeper, and away from the door and toward said latch keeper, whereby in the movement of said bar toward the door and away from said latch keeper said inturned arm acts against said roller to actuate said latch means to unlatched position.

3. In apparatus of the class described for a door, the combination of latch means, a latch keeper engageable by said latch means for retaining the door closed, a bar, parallel levers pivoted on the door and on said bar for mounting said bar on the door in spaced relation thereto, a roller connected with said latch means, said bar having an inturned arm extending toward the door and engaging said roller for actuating said latch means, said bar being adapted to swing on said parallel levers horizontally toward the door and away from said latch keeper, and away from the door and toward said latch keeper whereby in the movement of said bar toward the door and away from said latch keeper said inturned arm coacts with said roller to actuate said latch means to unlatched position, and yieldable means acting on said latch means and operable when pressure is released from said bar to return said latch means to latched position and move said bar away from the door and toward said latch keeper.

4. In apparatus of the class described for a door, the combination of latch means, a latch keeper engageable by said latch means for retaining the door closed, a bar, parallel levers pivoted on the door and on said bar for mounting said bar on the door in spaced relation thereto, a roller operative to actuate said latch means, said bar having an inturned arm extending toward the door and engaging said roller for actuating said latch means, said bar being adapted to swing on said parallel levers horizontally toward the door and away from said latch keeper, and away from the door and toward said latch keeper whereby in the movement of said bar toward the door and away from said latch keeper said inturned arm coacts with said roller to actuate said latch means to unlatched position, and stop means engageable by said inturned arm for limiting the movement of said latch means toward unlatched position and the movement of said bar toward the door after which continued movement of said bar forces the door to open position.

5. In apparatus of the class described for a door, the combination of latch means, a latch keeper engageable by said latch means for retaining the door closed, a bar, parallel levers pivotally mounted on the door and on said bar for mounting said bar on the door in spaced relation thereto, said bar being adapted to swing on said parallel levers horizontally toward and away from and laterally of the door, said bar having inturned arms extending toward the door, guide means on the door engageable by said inturned arms for guiding the movements of said bar, a roller operative to actuate said latch means and engageable by one of said inturned arms, whereby as pressure is applied on said bar in door-opening direction said one inturned arm acts against said roller to actuate said latch means to unlatched position.

6. In apparatus of the class described for a door, the combination of a latch bolt on the door for retaining the door closed, said latch bolt being slidable to latched and unlatched positions, a roller operative to actuate said latch bolt, a bar on the door pivotally mounted thereon on parallel levers for horizontal movement toward the door, said bar having an inturned arm engageable with said roller, whereby on move-

ment of said bar toward the door said inturned arm acts against said roller to actuate said latch bolt to unlatched position.

7. In apparatus of the class described for a door, the combination of a latch bolt on the door for retaining the door closed, said latch bolt being slidable laterally of the door to latched and unlatched positions, a roller arranged to actuate said latch bolt, a bar on the door pivotally mounted thereon on parallel levers for horizontal movement laterally of the door, said bar having an inturned arm engageable with said roller, whereby on movement of said bar laterally of the door said inturned arm actuates said roller to move said latch bolt to unlatched position.

8. In apparatus of the class described for a door, the combination of latch means for retaining the door closed, said latch means being slidable horizontally to latched and unlatched positions, said latch means having a forked extension with a roller mounted therein, a bar on the door in spaced relation thereto pivotally mounted thereon on parallel levers for horizontal movement toward and away from and laterally of the door, said bar having an inturned arm extending toward the door, said inturned arm being slidable in said forked extension and engageable with said roller, said bar being operative to unlatch said latch means on movement toward and laterally of the door, said inturned arm, on movement of the bar in the unlatching operation, sliding freely in said forked extension in the movement toward the door and bearing against said roller and drawing said latch means to unlatched position in the movement laterally of the door.

9. In apparatus of the class described for a door in a door jamb, the combination of latch keepers mounted on the door jamb, latch means on the door engageable with said latch keepers for retaining the door closed, links connected to said latch means, a rack and pinion operating through said links for actuating said latch means, a roller arranged to actuate said rack, a bar on the door pivotally mounted thereon on parallel levers for horizontal movement toward and away from the door, said bar having an inturned arm engageable with said roller, whereby on movement of said bar toward the door said inturned arm bears against said roller and thereby operates said rack and pinion and actuates said latch means to unlatched position.

10. In apparatus of the class described for a door in a door jamb, the combination of latch keepers mounted on the door jamb, latch means on the door engageable with said latch keepers for retaining the door closed, links connected to said latch means, a rack and pinion operating through said links for actuating said latch means, a roller operatively connected with said rack, a bar on the door pivotally mounted thereon on parallel levers for movement laterally of the door, said bar having an inturned arm engageable with said roller, whereby on movement of said bar laterally of the door said inturned arm imparts motion to said roller and thereby operates said rack and pinion and actuates said latch means to unlatched position.

11. In apparatus of the class described for a door in a door jamb, the combination of latch keepers mounted on the door jamb, latch means on the door engageable with said latch keepers for retaining the door closed, links connected to said latch means, a rack and pinion operating through said links for actuating said latch means, a roller connected with said rack, a bar on the

door pivotally mounted thereon on parallel levers for movement toward and away from and laterally of the door, said bar having an inturned arm engageable with said roller, whereby on movement of said bar toward and laterally of the door said inturned arm thrusts against said roller and thereby operates said rack and pinion and actuates said latch means to unlatched position, and stop means for limiting the movement of said bar in the unlatching operation after which continued movement of said bar will force the door to open position.

12. In apparatus of the class described for a door in a door jamb, the combination of latch keepers mounted on the door jamb, latch means on the door engageable with said latch keepers in opposite directions for retaining the door closed, links connected to said latch means, a rack and pinion, said links being attached to said pinion, said rack and pinion, operating through said links, being adapted to actuate said latch means in opposite directions to unlatched position, a roller operative to actuate said rack, a bar on the door pivotally mounted thereon on parallel levers for horizontal movement, and said bar having an inturned arm cooperating with said roller, whereby said bar, on pressure being applied thereto, acts against said roller and thereby operates said rack and pinion.

13. In apparatus of the class described for a door, the combination of latching bolt means for retaining the door closed, release means comprising a release bar adapted to be pushed toward the door in the releasing operation, substantially parallel links pivotally mounting said release bar on the door for swinging movement toward and away from the door, said latching bolt means comprising a bolt operating member, said release bar comprising an inturned arm member, and a roller carried by one of said members and adapted to coat with the other of said members whereby to transmit motion from said release bar to said latching bolt means.

14. In apparatus of the class described for a door, the combination of latching bolt means for retaining the door closed, release means comprising a release bar adapted to be pushed toward the door in the releasing operation, substantially parallel links pivotally mounting said release bar on the door for swinging movement toward and away from the door, said latching bolt means comprising a bolt operating member, said release bar comprising an inturned arm member, a roller carried by one of said members and adapted to coat with the other of said members whereby to transmit motion from said release bar to said latching bolt means, and stop means operative through the medium of said inturned arm member for limiting the swinging motion of said release bar toward said door, whereby to prevent the possibility of a person having his fingers pinched between said release bar and the door.

15. In apparatus of the class described for a door, the combination of latching bolt means for retaining the door closed, emergency release means comprising an emergency release bar adapted to be pushed toward the door in an emergency releasing operation, substantially parallel links pivotally mounting said release bar on the door for swinging movement toward and away from the door, said release bar comprising an inturned arm member, means for transmitting

motion from said inturned arm member to said latching bolt means for releasing the door when said release bar is pushed toward the door, and stop means operative through the medium of said inturned arm member for limiting the swinging motion of said release bar toward said door, whereby to prevent the possibility of a person having his fingers pinched between said release bar and the door.

16. In apparatus of the class described, the combination of latching means for holding the door closed, a release bar on the inside of the door, a pair of substantially parallel links pivotally mounting said release bar for swinging movement toward the door, an inturned arm projecting from said release bar, and means establishing a one-way motion transmitting connection between said inturned arm and said latching means.

17. In apparatus of the class described, the combination of latching means for holding the door closed, said latching means comprising a latch operating member, inside release means mounted on the inner side of the door comprising a release bar adapted to be pushed toward the door in a releasing operation, a pair of substantially parallel links pivotally mounting said release bar on said door for parallel link swinging motion toward and away from said door, and means rigid with said release bar and separate from said parallel links operative to engage said latch operating member for transmitting operating motion from said bar to said latch operating member.

18. In a latch bolt structure for a door adapted to be operated by an outside handle capable of being locked, the combination of latching means for holding the door closed, a release bar on the inside of the door, a pair of substantially parallel links pivotally mounting said release bar for swinging movement toward the door, an inturned arm projecting from said release bar, and means establishing a motion transmitting connection between said inturned arm and said latching means, whereby said inside release bar is always operative to release said latching means upon being swung toward said door even though said outside handle is locked.

19. In apparatus of the class described for a door adapted to be operated by an outside handle, which outside handle is capable of being locked or otherwise prevented from having effective operation, the combination of latching means for holding the door closed, said latching means comprising a latch operating member, inside release means mounted on the inner side of the door comprising a release bar adapted to be pushed toward the door in a releasing operation, a pair of substantially parallel links pivotally mounting said release bar on said door for swinging motion toward and away from said door, and means rigid with said release bar and separate from said parallel links operative to engage said latch operating member for transmitting operating motion from said bar to said latch operating member, whereby said inside release bar is always operative to release said latching means upon being swung toward the door even though said outside handle is then locked or otherwise prevented from having effective operation.
